UNITED STATES PATENT OFFICE.

JAMES A. LOYSTER, OF CAZENOVIA, NEW YORK.

TYPOGRAPHIC NUMBERING-MACHINE.

No. 830,445.

Specification of Letters Patent.

Patented Sept. 4, 1906.

Application filed November 4, 1905. Serial No. 285,827.

To all whom it may concern:

Be it known that I, JAMES A. LOYSTER, of Cazenovia, in the county of Madison, in the State of New York, have invented new and useful Improvements in Typographic Numbering-Machines, of which the following, taken in connection with the accompanying drawings, is a full, clear, and exact description.

This invention relates to certain improvements in typographic numbering-machines to be used in connection with a printing-press and in which one or more type or groups of type are brought into position to make their impression upon a suitable impression-receiving piece or pieces, such as a sheet or strips of card or paper.

The specific object is to provide an ordinary printing-press with means whereby a series of type or groups of type may be automatically selected and adjusted to print numbers of any denominations consecutively or progressively and to enable such numbers to be printed simultaneously in duplicate or as many times as may be desired. It is obvious, however, that instead of using numbering-type they may be substituted by other characters or combinations of characters—such as letters, syllables, words, and, in fact, any characters or symbols which it may be desired to print in sequence.

One of the essential purposes of my invention is to control the position of the several type by means of an intermittently advancing pattern sheet or strip of paper or equivalent material and to synchronize the movement of such pattern with that of the type-actuating mechanism, so that certain apertures in the pattern may be brought into registration with their corresponding selecting-pins and temporarily stopped to allow the pins to enter the registering apertures and determine the succeeding movement of the type-bearing elements, after which the printing-type and impression-receiving element are brought together to produce the desired impression or series of prints, as the case may be.

Other objects and uses will be brought out in the following description.

In the drawings, Figure 1 is a side elevation of a typographic numbering-machine embodying the essential features of my invention. Fig. 2 is a top plan of the same, and

Fig. 3 is a transverse sectional view taken on line $z-y$ of Figs. 1 and 2 looking in the direction indicated by arrow a .

The machine herein illustrated is adapted to print any number or combination of numbers of one, two, or three figures, as units, tens, and hundreds, from 0 to 999, inclusive, and to simultaneously print the same number two or more—in this instance three—times upon different parts of the same impression-receiving sheet or strip or upon different strips or cards. It will be evident, however, from the following description that numbers of higher denominations or combinations of an indefinite number of other characters may be printed and duplicated at each printing operation by simply increasing the number of type-wheels in each group and multiplying the number of groups of such type-wheels and their controlling mechanisms, as may be desired.

In order to clearly demonstrate the practicability of my invention, I have shown a pattern strip or sheet 10 as provided with a plurality of longitudinal groups of perforations 12, 13, and 14, which are cut in the central body of the pattern at predetermined intervals to control the action of the selecting-needles and type-wheels presently described, said pattern being also provided near its opposite edges with parallel lengthwise rows of apertures 11, which receive radial pins or teeth 15 of a rotary feeding-drum 16, whereby the pattern strip or sheet is advanced positively and uniformly in synchrony with the movements of other parts of the machine. This drum 16 is actuated intermittently to advance the pattern strip or sheet 10 step by step a predetermined distance at each operation, and for this purpose I provide the drum 16 with a ratchet-wheel 42, which is engaged and rotated one toothed space at a time by means of a pawl 48, which is mounted upon a concentrically-movable bell-crank 43 and is yieldingly held in engagement with the teeth of the ratchet-wheel by means of a spring 48'. The bell-crank 43 is oscillated back and forth against the action of a spring 46 by means of a cam 45, which is secured to a rotary shaft 49 and engages a roller 44 upon the arm of the bell-crank to which the pawl 48 is pivoted, the cam 45 having sufficient eccentric throw to rock the bell crank 43 and its pawl 48 one tooth-space of the ratchet-

75

105

wheel 42 against the action of the spring 46, which returns the bell-crank to its starting position at each cycle of operation of the cam 45.

5 The pattern sheet or strip 10 is preferably drawn in a horizontal position between suitable frictionally-retarded rollers 41, which tend to keep the operating part of the pattern taut as it is advanced by the drum 16.

10 The apertures 12, 13, and 14 of each group are spaced apart longitudinally a distance equal to the step-by-step movement of the pattern-sheet, so that each successive perforation of each group is advanced to a certain 15 position at each successive operation of the feeding-drum 16.

Mounted in the frame 47, one above the other, are a series of transverse perforated bars 17, 18, and 19, in which are loosely fitted 20 a series of groups of vertically-movable needles 20, 21, and 22, one group for each group of perforations 12, 13, and 14, respectively, each group comprising a series of, in this instance, ten needles, which are arranged in a 25 straight transverse line side by side and are so placed as to register with the apertures in the pattern-sheet with which they are associated as said pattern-sheet is advanced step by step—that is, the needles 20 of one group 30 are arranged in one transverse line to register with the apertures 12, while the needles 21 of the next adjacent group are arranged in a different transverse line to register with the apertures 13, and the needles 22 are disposed in 35 another transverse straight line to register with the apertures 14. Each needle is provided with a collar or shoulder 23 and a comparatively light coil-spring 24, which encircles the needle between the shoulder 23 and 40 transverse bar 17, each spring operating to depress its needle with its shoulder 23 resting upon a vertically-movable transverse bar 25, which serves as a yoke to elevate all of the needles simultaneously against the action of 45 their springs 24 and also to permit said needles to be simultaneously depressed by their respective springs, said yoke 25 being guided in its vertical movement upon suitable guide-rods 26, Figs. 1 and 3.

50 A series of groups of type-wheels 27 are rotatably mounted upon a transversely-movable carriage 29, each group comprising a series of, in this instance, three concentrically-arranged type-wheels of substantially the 55 same diameter, each group being arranged side by side one in advance of the other transversely of the machine a sufficient distance apart to permit the wheels of each group to rotate freely without friction with those of 60 the next adjacent group. Each type-wheel is provided with a series of, in this instance, ten peripheral numbering-type arranged, consecutively, from "0" to "9," inclusive, making in all ten characters corresponding to the 65 number of needles in each group. The type

wheels of each group revolving about the same axis are arranged to print numbers of progressively-increasing denominations—in this instance, units, tens, and hundreds—the wheels for printing numbers of like denomination of each group being arranged in transverse alignment and are connected for simultaneous action by transverse toothed racks 28, which mesh with gear-teeth 27', rigid with their respective type-wheels 27. It 70 will now be seen that each type-wheel is provided with gear-teeth rotating therewith and that all of the units-wheels of the several groups are actuated simultaneously by one of the toothed racks 28, the tens numbering-wheels are simultaneously actuated by a second toothed rack, and the hundreds numbering-wheels of all of the groups are actuated by a third rack, so that when one type-wheel is rotated to bring a certain type to the printing position the same type of the similar 75 wheels of the other groups are also brought to the printing position, whereby the same character or number is printed, in this instance, three times. These racks 28 are slidably mounted in suitable ways, one in advance of the other upon the carriage 29, directly beneath the lower ends of the needles and pattern-strip, each rack being slidable endwise transversely of the machine in the 80 same vertical plane as one of the groups of needles and is provided with a stop-shoulder or abutment 34, adapted to engage the needle of its group which may be projected through one of the apertures in the pattern 85 sheet or strip, as best seen in Fig. 3. It is now obvious that the rack 28, which actuates the hundreds numbering type-wheels is controlled by the needles of the group 20, while the rack which actuates the tens numbering 90 type-wheels is controlled by the needles of the group 21, and the rack which actuates the units numbering type-wheels is controlled by the needles of the group 22. It therefore follows that the apertures 12 in the pattern-sheet which are associated with the group of 95 needles 20 control the position of the hundreds numbering-wheels, while the apertures 13, associated with the needles 21, control the degree of movement of the tens numbering-wheels, and the apertures 14, coacting with the needles 22, control the position of the 100 units numbering-wheels. The carriage 29 is reciprocated transversely of the machine and pattern-strip a 105 distance equal to or slightly greater than the collective width of one of the groups of needles 20, 21, and 22 by means of a cam 33, which is secured to the rotary shaft 49 and is provided with a circumferential cam-groove 110 33', which receives a roller 32 on the carriage 29, the axial throw of the cam-groove 33' being, therefore, equal to or slightly greater than the transverse width of one of the 115 groups of needles, and the abutments 34 are 120

125 130 135

consequently normally spaced apart transversely of the machine a similar distance at one side of its corresponding group of needles.

Each rack 28 is yieldingly connected to the carriage 29 by a separate spring 31 of sufficient tension to advance the racks as the carriage is moved back and forth by the cam 33, so that the racks and carriage move as a unitary structure except as each rack may be retarded in its action by the engagement of one of the depressed needles with its corresponding abutment 34.

The main-driving shaft 49 is provided with a suitable sprocket-wheel 30, to which rotary motion may be imparted from any available source of power, (not necessary to herein illustrate or describe,) and to this shaft is secured a third cam or eccentric 35, which engages a roller 36 upon the free end of an oscillatory arm 37, the opposite end of said arm being secured to a rock-shaft 38 on the front end of the main supporting-frame 47. A second arm 39 is secured to the opposite end of this shaft 38 and has its free end extended rearwardly and connected by a link 40 to one end of the yoke 25, the other end of said yoke being connected by a similar link 40 to the intermediate portion of the rock-arm 37 which is located at the opposite side of the main frame. It is now apparent that at each cycle of rotation of the eccentric or cam 35, the arms 37 and 39 are oscillated vertically to reciprocate the yoke 25 a limited distance in the same direction through the medium of the links 40, the throw of the cam 35 being sufficient to cause the yoke 25 to engage the abutments 23 and elevate all of the needles 20, 21, and 22 clear of the pattern strip or sheet 10 and to allow such needles to be depressed by their respective springs through any of the apertures 12, 13, or 14 which may be registered with said needles and into the path of the movement of the abutments 34 of the racks 28, so that as the carriage 29 is advanced in the direction indicated by arrow α the racks 28 will be similarly advanced until the abutments 34 encounter any needles which may have been projected through apertures in the pattern-strip, whereupon the further advance movement of the rack thus engaged is arrested, while the carriage 29 continues to the limit of its movement against the action of the springs 31.

The pattern-strip 10 is inserted and fed between the bars 18 and 19, between the lower ends of the needles 20, 21, and 22, and upper ends of the abutments 34, the feed of the pattern-strip being intermittent and synchronized with the vertical movement of the yoke 25 in such manner that as the pattern-strip is advanced one step to bring one of the apertures 12, 13, or 14 of each group into registration with the corresponding needle or needles of the groups 20, 21, and 22 the further movement of the pattern-strip is tem-

porarily arrested, during which time the yoke 25 is depressed to allow the needle or needles to descend upon the pattern-strip or through its apertures which may be in registration with certain needles. Immediately succeeding the depression of the yoke 25 the carriage 29 is advanced in the direction indicated by arrow α , thereby advancing the racks 28 through the medium of the springs 31 until such racks are arrested by the engagement of the abutments 34 with certain pins or needles which may have been projected through registering apertures in the pattern-strip 10. This advance movement of each rack 28 causes the rotation of one of the type-wheels 27 of each group to bring the same numbering-type of such wheels into the same plane, after which the impression-receiving piece, as A, and type-wheels are brought together by any suitable mechanism (not necessary to herein illustrate or describe) for making an impression upon said impression-receiving piece A. This printing operation may be effected by bringing the type-wheels down upon the impression-receiving strip A or the latter may be pressed upwardly against the type-wheels in any well-known manner.

It will be seen upon reference to Fig. 3 that one pin or needle of each group is shown by dotted lines as depressed into the path of the shoulders 34—that is, the last needle of the series of the units group 22, the fourth needle of the tens series 21, and the sixth needle from the end of the hundreds series 20 are projected through registering apertures in the pattern-strip 10 and are engaged by the abutments 34 of their respective racks 28 as the carriage 29 is advanced in the direction indicated by arrow α . It therefore follows that the engagement of the abutment 34 of the hundreds-rack with the pin or needle of the hundreds group 20 will advance the hundreds type-wheels of each group six points to bring the printing-type "6" of each hundreds-wheel into the same printing plane, while the engagement of the abutment 34 of the tens-rack engaging the needle of the tens group will cause the rotation of the tens type-wheels of all of the groups to advance four points, bringing their type-numbers "4" to the same printing plane, and the shoulder 34 of the units-rack will engage with the needle of the units group and cause the units type-wheels of all of the groups to advance one space or point, thus bringing the type-number "1" of each unit-wheel into the same printing plane, so that when the type-wheels and impression-receiving strip or strips are brought together the numeral "641" will be impressed or printed in three different places upon said record-receiving strip or strips. The operation of bringing the type-wheels and record-receiving strips together may be effected automatically or by any other means.

as soon as the carriage 29 has been advanced to the limit of its movement by the cam 33, after which said cam operates to return the carriage to its starting position, during which 5 movement the springs 31 automatically return their respective racks 28 and type-wheels 27 to their normal starting positions, whereupon the cam 35, operating upon the arm 37, elevates the yoke 25 and needles 20, 21, and 10 22, after which the pattern-strip is advanced another step, and the operation just described is repeated for printing a different set of numerals.

What I claim is—

- 15 1. In a typographic numbering-machine, an intermittently-movable pattern strip or sheet, a plurality of type and means controlled by the pattern-sheet for causing the same or different type to be successively brought to the same printing position at each successive movement of the pattern-sheet, said means including a sliding member and separate devices for stopping said member in different positions.
- 25 2. In a machine of the class described, a printing-wheel having a plurality of type arranged in sequence on its periphery, means for rotating the type-wheel to successively bring each type to one and the same printing-point, a perforated pattern, and a series of 30 separately-acting selecting devices, each movable through one of the perforations of the pattern to engage and stop the type-wheel-actuating means.
- 35 3. In a machine of the class described, a group of separately-rotatable type-wheels, separate mechanisms for rotating said type-wheels, a perforated pattern and a plurality of series of separately-acting selecting devices, one series for each of the type-wheel-actuating mechanisms, each of said devices being adapted to enter one of the perforations of the pattern to engage and stop one of the type-wheel-actuating mechanisms.
- 45 4. In a machine of the class described, a carriage and means to reciprocate the same, a type-wheel on the carriage having a series of type thereon, a pattern sheet or strip and means controlled thereby for rotating the 50 type-wheel a predetermined degree during its forward movement with the carriage.
- 55 5. In a machine of the class described, a type-wheel having a plurality of type and gear-teeth, a carriage for the type-wheel, means to actuate the carriage, a rack meshing with said gear-teeth moving with the carriage to rotate the type-wheel, a pattern sheet or strip and separate devices controlled thereby for arresting the movement of the 60 rack at a predetermined point in its travel whereby the type-wheel is caused to rotate a predetermined degree.
- 65 6. In a machine of the class described a reciprocatory carriage, a type-wheel journaled on the carriage and provided with a
- plurality of type arranged in sequence upon its periphery, gear-teeth rigid with the type-wheel, a rack meshing with the gear-teeth, and yieldingly connected to the carriage, a pattern sheet or strip and means controlled thereby for engaging and arresting the rack during the forward movement of the carriage whereby the type-wheel is adjusted to bring a predetermined type to the printing-point.
- 70 7. In a machine of the class described, a reciprocatory carriage and its actuating means, a group of type-wheels rotatably mounted on the carriage and each having a plurality of type, and gear-teeth rigid therewith, toothed racks each meshing with the 80 gear-teeth of one of the type-wheels and yieldingly connected to the carriage to move therewith, movable stop devices each adapted to engage and arrest the advance movement of one of the racks during the forward 85 movement of the carriage, whereby the type-wheels are separately adjusted to bring one of their type to the printing-point, and a pattern sheet or strip controlling the action of said devices.
- 90 8. In a machine of the class described, a reciprocatory carriage, a type-wheel rotatably mounted on the carriage and provided with a plurality of type and gear-teeth rigid therewith, a rack meshing with said gear-teeth and moving with the carriage, said rack being loose upon and yieldingly connected to the carriage and provided with an abutment, a stop movable into and out of the path of the said abutment, and a pattern 95 sheet or strip controlling the action of said stop.
- 95 9. In a machine of the class described, a reciprocatory carriage and its actuating means, a type-wheel rotatably mounted upon the carriage and provided with a series of type each adapted to be brought to the same printing-point by the rotation of the wheel, said type-wheel being provided with a series of concentric teeth, a toothed rack 100 loose upon but movable with the carriage and meshing with said teeth of the type-wheel, a series of movable stops corresponding in number to the number of type on a wheel and each adapted to be moved into engagement with the rack to arrest its movement during the forward movement of the carriage and a pattern strip or sheet controlling the action of the said stops.
- 105 10. In a machine of the class described, a carriage and its actuating means, a type-wheel rotatably mounted on the carriage and provided with a plurality of type, a movable stop and means engaged thereby during the forward movement of the carriage for rotating the type-wheel, and a pattern sheet or strip controlling the action of the said stop.
- 110 11. In a machine of the class described, a carriage and its actuating means in combination with a group of separately rotating type- 115
- 120 12. In a machine of the class described, a carriage and its actuating means, a type-wheel rotatably mounted on the carriage and provided with a plurality of type, a movable stop and means engaged thereby during the forward movement of the carriage for rotating the type-wheel, and a pattern sheet or strip controlling the action of the said stop.
- 130 13. In a machine of the class described, a carriage and its actuating means in combination with a group of separately rotating type-

wheels mounted on the carriage and having a common axle, each type-wheel being provided with a plurality of type, separate devices for rotating said type-wheels during the forward movement of the carriage and a pattern sheet or strip controlling the action of said devices.

12. In a machine of the class described, a carriage and its actuating means, a group of 10 separately rotatable type-wheels mounted on the carriage and each provided with a plurality of type, separate abutments moving with the carriage and each operatively connected to one of the type-wheels, stops movable into and out of the path of said abutments, and a pattern sheet or strip controlling the action of said stops.

13. In a machine of the class described, a series of type-wheels mounted on separate 20 axes and each provided with a plurality of type, means for shifting said axes simultaneously in the same direction, a movable stop and means engaged thereby during the shifting of the type-wheel axes for rotating said 25 type-wheels simultaneously through equal arcs, and a pattern strip or sheet controlling the action of said stop.

14. In a machine of the class described, a reciprocatory carriage and its actuating 30 means, a type-wheel rotatably mounted on the carriage and provided with a plurality of numbering-type consecutively arranged upon its periphery, gear-teeth rigid with the type-wheel, a rack loosely mounted on the carriage and meshing with said gear-teeth, a spring connecting the rack to the carriage, an abutment rigid with the rack, a series of stops movable into and out of the path of the said abutment and a perforated pattern-sheet 40 controlling the action of the said stops.

15. In a machine of the class described, a reciprocatory carriage and its actuating means, a group of type-wheels rotatably mounted upon the same axis on the carriage 45 and each provided with numbering-type consecutively arranged upon its periphery, each type-wheel being provided with gear-teeth, separate toothed racks loosely mounted on the carriage and each meshing with the gear-teeth of one of the type-wheels, springs each connecting one of the racks to the carriage, said racks being each provided with an abutment and separate groups of stops one group for each type-wheel, the stops of each group 50 being movable into and out of the path of one of the abutments, and a perforated pattern sheet or strip controlling the action of the said stops.

16. In a machine of the class described, a reciprocatory carriage, separate type-wheels 60 rotatably mounted upon the carriage in substantially the same transverse plane and each provided with gear-teeth and with a plurality of type, a rack meshing with the gear-teeth of all of the said type-wheels and 65 loosely mounted on the carriage to move therewith, said rack being provided with an abutment, a group of stops arranged at different distances from the abutment and movable into and out of its path, and a perforated pattern-sheet controlling the action of said stops.

17. In a machine of the class described, a reciprocatory carriage, a plurality of groups of type-wheels rotatably mounted upon the 75 carriage and each provided with a plurality of type, each type-wheel being provided with concentric gear-teeth, a plurality of teeth-racks mounted on the carriage to move therewith, each rack meshing with the gear-teeth 80 of one of the type-wheels of each group and provided with an abutment, separate groups of stops, those of each group being movable into and out of the path of the movement of one of the abutments, and a perforated pattern strip or sheet controlling the action of 85 said stops.

18. In a typographic numbering-machine, a type-carrier, means to actuate the carrier to bring each type to the same printing-point, a pattern and a series of separately-actuating selecting devices controlled by the pattern to engage and stop the actuating mechanism for the type-carrier.

19. In a machine of the character described, a type-wheel having a plurality of type, means to rotate the type-wheel to bring each type to the same printing-point, a pattern and a series of separately-actuating selecting devices controlled by the pattern to engage and stop the type-wheel-actuating means.

20. In a machine of the character described, a rotary type-wheel and actuating means therefor, a perforated pattern, a series 105 of separately-actuating selecting devices controlled by such pattern to enter the perforations therein and engage and stop the type-wheel-actuating means.

In witness whereof I have hereunto set my hand on this 1st day of November, 1905.

JAMES A. LOYSTER.
